UNITED STATES PATENT OFFICE.

DELVIN S. LERMOND, OF DELPHI, INDIANA.

RAILROAD CATTLE-GUARD.

SPECIFICATION forming part of Letters Patent No. 355,183, dated December 28, 1886.

Application filed August 14, 1886. Serial No. 210,947. (No model.)

To all whom it may concern:

Be it known that I, DELVIN S. LERMOND, of Delphi, in the county of Carroll and State of Indiana, have invented a new and useful Improvement in Railroad Cattle-Guards, of which the following is a specification.

My invention consists in an improved railroad cattle-guard, which will be hereinafter fully described and claimed.

Referring to the accompanying drawings, Figure 1 is a top plan view of my invention, showing the same applied in its operative position. Fig. 2 is a vertical sectional view taken on line *x x*, Fig. 1; and Fig. 3 is a vertical sectional view taken on line *y y*, Fig. 1.

The same letters of reference indicate corresponding parts in all the figures.

Referring to the several parts by letter, A represent the ties on which the rails B are supported, these parts being of the usual construction.

The guard consists of the central section, C, which fits between the rails, and the side sections C' C', which are secured on the outer sides 25 of the rails, as shown, the whole guard being about nine feet square over all. Each section is composed of the parallel side pieces, D D', which may be made of either cast or wrought iron, these side pieces being reduced at their

ends on the upper sides thereof, and having the apertures D' formed vertically through their 30 ends for the bolts E, which secure the sections of the guard removably to the ties in their operative positions. The side pieces of the

guards are formed of iron plates or strips of the requisite length, and usually five and one-half inches wide, one inch of the entire upper 35 edge of this piece being bent over at right angles to form the top of the side piece, while

one and one-half inch of the entire lower 40 edge is bent parallel to the upper edge to form the lower edge or bottom of the side piece, both of the said edges being bent inwardly toward the slats to prevent the ends of the

same from moving up or down. Quadrangular 45 iron bands F are secured between the top and bottom flanges of the side pieces by riveting them thereto, so as to form between them the slanting spaces or sockets F', the middle portion of the inner face of each side piece having a vertical recess or socket, in which fits a vertical 50 slat, G. The quadrangular bands F also form

braces for the top and bottom of the channel-irons or side pieces, D. In the inclined sockets fit the ends of the slats H, which may be made 55 of wood, and which are usually one and one-half inch thick by seven inches wide, the inner faces of the side pieces being three inches high, and when the slats are secured in the sockets at an angle of about thirty degrees their upper edges 60 project an inch above the tops of the side pieces, while their lower edges are preferably cut off or beveled, as shown, so as to lie flush with the lower edges of the side pieces. The upper edges of the slats project above the rails, as it 65 is necessary to use wide slats to form an effective guard, and the ends of the slats must therefore be reduced to form tenons that enter the sockets formed between the bands F. The side pieces are held firmly together by the rods K, 70 the outer faces of the side pieces being countersunk at those points for the reception of the heads and nuts of the rods.

To the outer sides of the side pieces are riveted the short strips of iron L, the upper and 75 lower ends of which are bent outwardly at right angles and inclined at the same angles as the slats themselves, each piece thus forming two inclined lugs, L'.

My improved cattle-guard is bolted down 80 on the common track-ties without disturbing the road-bed in the least, thus saving the expense of digging a ditch in the usual way, the middle section fitting between the rails, while the two side sections are secured on the outer 85 sides of the rails, as shown, making the entire guard about nine feet square.

It will be seen that by arranging the slats slanting from the center toward each end, when stock step on the guard from either end, their 90 feet will slide down between the slats, which thus catch the feet and prevent the stock from walking up on the guard, while there is nothing to prevent the stock from backing off the guard. The slanting lugs on the outer faces 95 of the side pieces will prevent the stock from stepping between the side pieces and the rails.

When the road-bed or track needs repairs, it is only necessary to unfasten the bolts which 100 secure the side pieces to the ties and lift the guard to one side.

From the foregoing description, taken in connection with the accompanying drawings, the construction and advantages of my im-

proved railroad-guard will be readily understood. It will be seen that it is simple and cheap in its construction, while at the same time it is exceedingly efficient in its operation.

5 Having thus described my invention, what I claim as new, and desire to secure by Letters Patent, is—

1. The combination of the side pieces having the inwardly-bent upper and lower longitudinal edges, the quadrangular bands secured between the said edges to form the inclined sockets, the inclined lugs secured on the outer sides of the side pieces, the slats, and the rods connecting the side pieces together, substantially as described.

10 2. The combination, in a cattle-guard, of the side pieces formed of angle-irons, and the spaced quadrangular bands secured within the

side pieces to the top and bottom thereof, to brace the same and form inclined sockets, with 20 the slats resting at their ends in the said sockets, substantially as set forth.

15 3. The combination, with the side pieces formed of channel-irons provided with spaced quadrangular bands secured to the top and bottom thereof, to brace said channel-irons and form sockets, of the slats extending above the tops of the channel-irons, and reduced at their ends to fit within the said sockets, and rods and nuts securing the side pieces together, substantially as set forth.

DELVIN S. LERMOND.
